LIGHTING FIXTURE

Stanley H. Barnes, New Rochelle, N. Y., assignor
to Gleason-Tiebout Glass Company, Maspeth,
Long Island, N. Y., a corporation of New York

Application April 22, 1932, Serial No. 606,768

7 Claims. (Cl. 240—78)

The present invention relates to lighting fixtures and is more particularly directed toward indirect lighting fixtures having a luminous central portion or disc directly supported from above (as for example by a socket cover) and a light deflector of larger diameter supported from the central luminous disc.

Where both parts are made of glass, the inner edge of the outer or larger glass part rests directly on the peripheral edge of the smaller or disc-like part. This avoids the use of metal rings and permits the character of the light transmitted to be controlled entirely by the glass parts.

The present invention contemplates a fixture of this nature wherein the disc is secured to the socket cover in such a manner that it can be easily detached to facilitate assembly, relamping, and cleaning.

The invention also contemplates a fixture wherein the outer deflector, which may be made of glass or opaque material, is supported from the lower luminous disc in such a way as to securely lock the supporting means for the luminous disc in place.

25 Other and further objects of the invention will appear as the description proceeds.

The accompanying drawing shows, for purposes of illustrating the present invention, three of the many embodiments in which the invention may 30 take form, it being understood that the drawing is illustrative of the invention rather than limiting the same. In this drawing:

Fig. 1 is a vertical sectional view with parts in elevation, showing one form of lighting fixture;

35 Fig. 2 is an inverted plan view of the same on a larger scale; and

Figs. 3 and 4 are views similar to Fig. 1 showing modified forms of construction.

In the drawing, a conventional support or suspension for a lighting fixture is indicated at 10. It carries a lamp socket 11, a lamp bulb 12, and socket cover 13 in the usual manner.

As shown in Fig. 1, the socket cover 13 is provided with a lower bead 14 slotted as indicated at 15 to receive lengths of bead chain 16. The lower lengths of this bead chain have larger balls 17. These lengths of bead chain support a glass member 18 of suitable ornamental shape and provided with slots 19 adapted to accommodate the bead chain 16 and with pockets 20 to receive the balls 17 at the lower end of the bead chain.

When the parts are in the position indicated in the drawing, the disc 18 will be suspended a suitable distance below the lamp bulb. The upper edge of the disc is preferably shouldered as in-

dicated at 21 so as to provide a seat 22 for the inner edge 23 of a deflector 24, preferably made of glass. When this deflector is in place, as shown, it closes the slots 19 so that the supporting chains 16 cannot then be removed from the 60 slots.

When one desires to take down the fixture for any purpose, the shade 24 is lifted or raised up by one hand while the other hand tilts the disc. Two of the chains readily disengage from the 65 slots and then the disc may be tilted the other way to release the other chain.

Fig. 1 also shows the use of a metal cap or cover 25 secured to the disc 18 by a central bolt 26. When this cover is used, the light is cut off 70 and the brightness of the outer part of the disc made more noticeable by contrast. This is especially of value where an opaque or substantially opaque shade 24 is employed.

In the form of construction shown in Fig. 3, the socket cover 30 is provided with slots 31 and holes 32 adapted to receive the upper hooked ends 33 of wires 34. The lower ends of these wires have enlargements or heads as indicated at 35, and are received in slots 36 in a glass disc or cup 37. These wire members are preferably under slight tension and press inwardly so as to securely hold the glass disc in place. The deflector or shade 38 may be of glass, metal, or other suitable material, and locks the suspension wires in place to prevent accidental separation. The disc is removed by raising and tilting so that two of the wires pass out through the slots, whereupon the disc is moved to separate it from the other wire.

The fixture shown in Fig. 4 has a glass shade 40 having a central opening 41. It is supported by a glass disk or plate 42 on which it directly rests. This disc is drilled to receive rods 43 threaded to receive knobs 44. The rods depend from a socket cover or other support. Instead of rods, bead chain could be employed. The diameter of the opening in the shade is preferably just large enough to receive the rods 43 so that the glass shade may be centered on the disc without requiring a shoulder.

The discs or cups 18 or 37 may assume various ornamental shapes or may be in the form of a substantially flat piece of glass or other light diffusing material. They are preferably made of pressed crystal glass, clear or colored, rendered more or less diffusing by sand blasting or etching in whole or in part. These discs present comparatively deep sections as indicated at A through which light passes so as to provide a 110

comparatively bright ring of luminous material, of less optical density than the shade 24, thereby adding an effective form of trimming to the fixture.

5 It will, of course, be understood that the present invention is not necessarily limited to lighting fixtures which are open at the top for it may be applied to totally enclosed fixtures made with a one piece or a two piece globe open at 10 the bottom. It then provides a convenient means, not only for supporting the shade or globe but for affording access to the lamp bulb from underneath. It also provides for luminous trimming to the fixture which enhances its appearance.

15 It is obvious that the invention may be embodied in many forms and constructions, and I wish it to be understood that the particular forms shown are but a few of the many forms. Various modifications and changes being possible, I do not otherwise limit myself in any way with respect thereto.

What is claimed is:

20 1. A lighting fixture comprising a pendant lamp socket, a socket cover about the socket, a lamp bulb in the socket, a translucent disc underneath the lamp bulb, the disc having peripheral slots, disc supporting members secured to the socket cover and passing through the slots, and 25 a bowl resting on the disc and closing the slots.

25 2. A lighting fixture comprising a pendant lamp socket, a socket cover about the socket, a lamp bulb in the socket, a translucent disc underneath the lamp bulb, the disc having peripheral slots, disc supporting members secured to the socket 30 cover and passing through the slots, and a bowl having a bottom opening smaller than the disc and

large enough to receive the supporting members, the bowl resting on the periphery of the disc and extending upwardly and outwardly.

3. An indirect lighting fixture having a bowl, open at the bottom, a diffusing glass disc having a peripheral seat to receive the lower edge of the bowl, and radial slots extending from its outer edge across the seat and into the body of the disc, and supporting members engaging the under surface of the disc and extending upwardly through the slots. 80 85

4. A lighting fixture as claimed in claim 3, wherein the supporting members are in the form of lengths of bead chain having enlarged balls at the lower end, and the disc has ball receiving 90 pockets. 95

5. A lighting fixture as claimed in claim 3, wherein the supporting members are in the form of lengths of resistant wire tensioned to press inwardly. 95

6. A lighting fixture comprising a diffusing bowl open at the bottom, and a diffusing closure member for the hole, the closure member being provided with a thick peripheral edge of less density than the bowl so as to provide a bright 100 ring of light below the bowl. 100

7. A lighting fixture comprising a centrally located glass disc, supports extending from above the disc down through openings in the disc near its edge and having enlargements below the disc 105 to support the disc, and a glass diffusing bowl extending upwardly and outwardly from the disc, the bowl having a central aperture to receive the supports, and resting directly on the upper surface of the glass disc. 110
